STRIP UNCOILER

Howard H. Talbot and Maurice P. Sieger, Pittsburgh, Pa., assignors to United Engineering & Foundry Company, Pittsburgh, Pa., a corporation of Pennsylvania

Application March 27, 1935, Serial No. 13,218

13 Claims. (Cl. 242—78)

This invention relates to an improvement in apparatus for unwinding coils of steel or other permeable strip.

An object of the invention is to provide an apparatus of this character which is sturdy of construction, simple, efficient and dependable in operation, and which is adapted to feed the strip as it is unwound from the coil, in a convenient and effective manner, into the work or handling device with which it is used.

Another object is to provide in an uncoiler of this type for maintaining the axis of the coil in a relatively fixed position while it is being uncoiled and for stripping the loose end from the coil to inaugurate the uncoiling by means of a magnetically operable gripping device.

These and various other objects as well as the various other novel features and advantages of the invention will be apparent when the following detailed description is read in conjunction with the accompanying drawings of which Fig. 1 is a plan view of an uncoiler constructed in accordance with the invention; Fig. 2 a longitudinal section taken on the line II—II of Fig. 1; Fig. 3 a horizontal section taken on the line III—III of Fig. 2; Fig. 4 a transverse section taken on the line IV—IV of Fig. 1; and Fig. 5 a view partly in section and partly in elevation looking toward the front of the apparatus.

Referring in detail to the drawings the numerals 1 and 2 designate a pair of axially adjustable spindles for supporting a coil while it is being unwound. To facilitate the insertion of these spindles in the ends of the coil they are tapered somewhat at their inner ends. To also adapt them to straighten the sides of a coil when they are moved thereinto, in the event the turns of the coil are out of alignment and keep the latter in alignment while the coil is being unwound, end guards 3 are provided on the outer ends of the hub portions 4, while to permit their being separated to receive a coil and to be inserted in the ends of a coil they are mounted in a pair of pyramid-shaped supports 5 which are in turn slidably mounted on a pair of base plates 6.

For adjusting these supports 5 to move the spindles 1 and 2 in the manner referred to, they are provided on their bottoms with bosses 7 which are projected through aligned elongate slots 8 located in the tops of the base plates 6. Through these bosses there is extended and threadedly engaged therewith a pair of screws 9 which are held against endwise movement in the bases 6 and provided with reverse threads

so that they produce opposite movement of the two spindles when turned in the same direction. For turning such screws gears 11 are provided on their outer ends and connected to a common drive shaft 12 through the aid of idler gears 13 and driving gears 14 which are keyed to this drive shaft. The latter is in turn connected at one end to a driving motor 15 arranged at the side of the uncoiler.

To maintain the spindles 1 and 2 in axial alignment while they are being moved, the base plates 6 are provided with upwardly and outwardly projecting shoulders 16 on their lateral edges and the spindle supports 5 with edge flanges 17 which engage these shoulders.

In order to load a coil onto the spindles 1 and 2, and to do so efficiently and conveniently irrespective of the diameter of the coil, a vertically adjustable coil-receiving and manipulating combination platform and cradle is provided directly below the spindles. This combinational device as shown most clearly in Figs. 1, 2 and 3 comprises a substantially horizontally disposed platform 19 which is pivotally supported at its coil-receiving end by a shaft 21 that is mounted in suitable bearing supports 22, and preferably at an elevation in alignment with a conveyor or chute 23 by means of which the coils are delivered to it. In a downwardly convexed beam-like projection 24 provided on the movable end of this platform there are mounted two sets of spaced rollers 25 and 26 which form a supporting cradle for a coil. The one set of these rollers located nearest the pivoted end of the platform is arranged flush with the surface thereof while the second set is disposed at a somewhat higher elevation so that a coil can be readily rolled over the first set into the cradle and be retained therein by the second set, the rollers being used to permit the coil to be readily rotated on the cradle for a purpose which will presently appear.

To effect rotation of a coil mounted on this cradle, a sprocket wheel 27 is mounted between the forward rollers 25, on their supporting shaft 28, and a chain 29 extended from this sprocket wheel to a driving sprocket 31 secured to a drive shaft 32 mounted in the bottom of the platform at a point nearer to the platform-supporting shaft 21 where the vertical movement of the platform is more limited. For driving the latter sprocket wheel 31 a motor 33 is connected to its supporting shaft 32 by means of an intermediary shaft 34 and a pair of flexible couplings 35 which permit the necessary movement of the platform without interfering with the drive.

For raising the coil-supporting cradle so that the spindles 1 and 2 can be inserted in the ends of a coil mounted thereon and for also lowering the cradle away from the coil after it is mounted on the spindles, a jack-type screw rod 36 having a thread in its lower end is provided. The upper end of this screw rod is connected by means of a link 37 and pin 38 to a bracket 39 on the end of the frame-work 24. Its lower end is engaged 5 in an internally threaded screw block 41 which is mounted against axial movement in a housing 42. On the periphery of the threaded block 41 there is formed a worm gear 44 which is meshed with a worm 45 mounted on a shaft 46 that is 10 in turn operably connected to a reversible driving motor 47 located at the side of the uncoiler.

Above the spindles 1 and 2 there is arranged an electromagnet 48 for stripping the free end from a coil mounted on the spindles 1 and 2 and in- 20 augurating the unwinding operations. This magnet is provided with a length sufficient to accommodate the widest strip the uncoiler is capable of handling, and is mounted for movement toward and from the spindles in the ends of a pair of 25 curved arms 49 which are in turn secured to a shaft 51 that is supported on a pair of side frames or girders 52 directly above the spindles 1 and 2. These frames 52 are themselves supported above the spindles on suitable piers 53 and 54 located 30 at the sides and ends of the uncoiler.

For lowering and raising the magnet 48 a gear segment 55 is mounted on the end of its supporting shaft 51 and meshed with a pinion 56 mounted on the drive shaft 58 of a driving motor 57. To 35 insure the face of the magnet 48 making the proper contact with the surface of a coil mounted on the spindles 1 and 2, irrespective of the diameter of the coil, it is pivotally mounted in the ends of its supporting arms 49. Its pivotal movement, 40 however, is limited so that it can not get out of position, by suitable bosses 58 provided on its outer ends which are arranged to engage cooperating bosses 61 provided on the inner faces of its supporting arms 49. Although not shown, as such 45 is deemed unnecessary, any suitable circuit may be employed for supplying current to the magnet.

In order to permit the face of the magnet 48 to contact the periphery of a coil mounted on the spindles 1 and 2 so that it can grip the outer end thereof and at the same time adapt the guards 3 to line up the edges of the coil, the guards are 50 made non-circular in shape. That is, over certain portions they do not project beyond the periphery of the coil, while at others they do. Thus 55 the magnet may be contacted in the narrow portions with the coil without striking the guards, and at the same time the guards are capable of engaging and straightening the edges of the coil. In the present embodiment of the invention the 60 guards are made in the shape of a triangle. An advantage of this is that due to gravity they normally assume a position with one base of the triangles parallel to the horizontal and one of the short sides in the proper position for the magnet 65 to contact the coil. To facilitate the guards 3 always assuming their normal position when free to do so, the shafts 10 on which the spindles are mounted are provided with anti-friction bearings so that the spindles will rotate with the greatest 70 possible ease.

Another feature of the guards 3 is that their inner faces are inclined outwardly sufficiently from their centers so that the strip can be readily pulled from a coil mounted on the spindles without the guards binding the edges of the strip. In 75

addition they are provided with radially disposed teeth-like projections 20 on the surface thereof adjacent the periphery of the spindles. The purpose of these is to bite into the edges of the innermost convolutions of the coil so that the turning 5 of the coil can be resisted by braking the spindles and without interfering with the unwinding of the strip.

For pulling the strip from the coil after the end thereof has been pulled out by the magnet 10 48 an upper and a pair of lower stripping and straightening rolls 62, 63 and 64 respectively are employed. The upper of these rolls is adjustably mounted in suitable chucks 65 located in vertically disposed windows 66 provided in the side 15 frames 52. For adjusting these chucks, so as to vary the pressure with which they engage the strip, adjusting rods 67 are secured to their upper ends, being extended upwardly through the tops of the frames 52, and equipped at their upper ends with suitable adjusting nuts 68. These nuts are disposed to bear against the upper ends of a pair of sleeves 69 threadably mounted in the frames 52 and through which the rods are projected. Below such sleeves a pair of coil springs 25 71 is arranged, being utilized to provide the roller 62 with a resilient mounting. For turning such sleeves 69 they are provided with non-circular tool-receiving upper ends 72 and for locking them in position lock nuts 73 are provided. When it is desired to adjust the upper roll 62 the lock nuts 73 are released and the nuts 68 and the sleeves 69 turned until the desired adjustment is obtained and the lock nuts 73 then returned to place.

The two lower stripping and straightening rolls 63 and 64 are mounted in a pair of side frames 74 which are in turn pivotally supported, at their ends opposite to the rollers, in the main side frames 52 by suitable stud shafts 75. The purpose of this latter mounting is to provide for moving these lower rollers out of the way of the magnet 48 when it is lowered to engage the strip and then back into their strip engaging positions adjacent the upper roller 62 after the end 40 of the strip is pulled up under the latter roller 62 by the magnet. It is to permit the magnet being operated in this way without striking the upper roller that its supporting arms 49 are made in the shape of a bell crank.

To actuate the supporting frames 74 for the lower rollers 63 and 64 in the manner referred to, rigid connecting rods 76 are pivotally attached to them adjacent their free ends and to a pair of cranks 77 mounted on a drive shaft 78 which is 55 in turn connected to a driving motor 79 by means of a drive shaft 81 and a gear reducing unit 82. These connecting rods and cranks are so proportioned that with each revolution of the cranks the frames 74 are moved from their upper to their lower positions and back again. To automatically stop them in these two positions a limit switch 83 of suitable construction is connected to the gear unit 82 for rotation thereby, and to adapt the rods 76 and cranks 77 to provide the greatest 60 possible support for the rollers 63 and 64 the cranks 77 are designed to position the rollers in the upper position when they are in direct alignment with the rods 76.

For unwinding a coil after its end is engaged 70 between the rolls 62, 63 and 64 a driving motor 84 is connected to the upper roll 62 by a chain 85 which is mounted on a sprocket 86 secured to the end of the drive shaft 87 of the motor 84 and a sprocket wheel 80 secured to the neck of the roll 75

62 outside of the supporting frame 52. To disconnect this latter motor from the roll 62 a clutch 88 is connected in the drive shaft 87.

To adjust the uncoiler for operation the 5 spindles 1 and 2 and the combination platform and cradle 19 are first adjusted to their coil receiving position. A coil is then delivered from the coil supplying chute 23 onto the cradle formed by the rolls 25 and 26, with its turns running in 10 the right direction for uncoiling. The motor 47 for the elevating screw 36 of the platform and cradle is next started and the coil raised until its center is in position to receive the spindles 1 and 2. When in such position the rolls 25 are actuated 15 by their driving motor 33 until the end of the coil is in position to be engaged by the magnet 48. The motor 15 for adjusting the spindles is then operated until the spindles are properly engaged in the coil. The motor 47 for the elevating screw 56 is then reversed and the cradle lowered away from the coil and into position to receive the next subsequent coil. At this point the motor 79 is set in motion and operated until the lower stripping and straightening rolls 63 and 64 20 are out of the way of the magnet 48. The motor 57 is then operated in the proper direction until the electromagnet 48 contacts the coil. As soon as this occurs the magnet is energized and the motor 57 reversed. As the magnet moves back 25 towards its normal elevated position it lifts the end of the coil up under the upper stripping roll 62 and in doing so bends the end sufficiently to assist in passing it out of the uncoiler over a guide 89 provided at the pivoted end of the side frames 35 74. As soon as the magnet reaches its upper position the motor 79 is set in motion and the rolls 63 and 64 actuated to their upper position and stopped in readiness to pull the strip from the coil. The magnet is then deenergized and the 40 driving motor 84 for the upper roll 62 either started or connected by the clutch 88 to the upper roll and the latter operated until the coil is unwound. As soon as the unwinding is completed the spindles are returned to their coil receiving 45 position and the pinch rolls 63 and 64 lowered to their lower position placing the apparatus in readiness to receive another coil. To tension the strip in the coil as it is being unwound or to resist the turning of the coil for any reason whatsoever a brake 90 is provided being arranged to operate on a brake drum 91 secured to the spindle 2 and equipped with a hydraulic motor 92 for operating it.

As will be appreciated by those skilled in the 55 art, such an apparatus provides an effective and efficient means for uncoiling steel or other permeable strip, one which is simple and easy to operate, requires but little manipulation of the coils and which is dependable in operation. It 60 will also be appreciated that through the adjustment of the upper stripping rolls 62 of the use of the two spaced lower stripping rolls 63 and 64 the stripping mechanism can be readily adjusted to handle different thicknesses of strip and to 65 produce varying degrees of straightening in the strip. Another advantage of it is that it is capable of handling coils of varying widths and diameters and of expeditiously uncoiling them. In addition while not shown it is also apparent 70 that automatic controls can be readily applied to most of the operating motors although manual control is contemplated by the foregoing description.

According to the provisions of the patent 75 statutes, we have explained the principle and

mode of operation of our invention and have illustrated and described what we now consider to represent its best embodiment. However, we desire to have it understood that, within the scope of the appended claims, the invention may be practiced otherwise than as specifically illustrated and described.

We claim:

1. In an apparatus for uncoiling coiled permeable metal strip the combination of means for engaging a coil at its center and supporting it for rotation, an electromagnet for engaging the free end of a coil, a pivotally mounted crank for supporting said magnet, and means for operating said crank to move said magnet in an 15 arcuate path relative to said support to strip the free end from the coil.

2. In an apparatus for uncoiling coiled permeable metal strip the combination of means for engaging a coil at its center and supporting it 2 for rotation, means for delivering the coil to said supporting means, an electromagnet for engaging the free end of the coil mounted on said support, a pivotally mounted crank for supporting said magnet, and means for moving said crank to 24 move said magnet relative to said support at an angle to the periphery of the coil to strip the free end from the coil.

3. An apparatus for unwinding coils of permeable strip comprising a pair of axially adjustable spindles for engaging the center of a coil at its ends and supporting it for rotation, means for delivering a coil to a position in axial alignment with said spindles, means for adjusting said spindles to engage them in the ends of 35 a coil mounted on said delivery means, a magnet for engaging the free end of a coil when mounted on the spindles, and a pivotal crank for supporting and moving said magnet in an arc into and out of engagement with the coil. 40

4. An apparatus for unwinding coils of permeable strip comprising a pair of axially adjustable spindles for engaging the center of a coil at its ends and supporting it for rotation, means for delivering a coil to said spindles, means 45 for adjusting said spindles to engage them in the ends of the coil, means on said spindles for straightening the sides of the coil as they are moved into the ends thereof, an elongate magnet for engaging the free end of a coil mounted 50 on the spindles across its width, and means for moving said magnet into and out of engagement with said coil, the straightening means being of sufficient diameter to span the ends of the coil but having aligned portions cut away to permit the magnet to engage a coil shorter than 55 the magnet.

5. An apparatus according to claim 4 characterized by said straightening means being of triangular shape. 60

6. An apparatus according to claim 4 characterized by said straightening means being of triangular shape and adapted to normally maintain said spindles in a position of rest. 65

7. An apparatus for unwinding coils of permeable strip comprising a pair of axially adjustable spindles for engaging the center of a coil at its ends and supporting it for rotation, means for delivering a coil to a position adjacent 70 said spindles, means for holding a coil in a selected position on said last-mentioned means, means for moving said first-mentioned means to register a coil mounted thereon in position to receive said spindles, means for adjusting said spindles to engage them in the ends of the coil, 75

means on said spindles for straightening the sides of a coil as the spindles are moved into a coil, a magnet for engaging the free end of a coil, means for moving said magnet into and out of engagement with a coil mounted on said spindles, said straightening means being constructed to permit such operation, a stripping roll disposed to engage the strip as it is pulled from the coil by the magnet, a second stripping roll mounted for movement to and from the first-mentioned roll but disposed when in operative position in the path which the magnet travels in its movement to and from the coil, and means for moving said second roll out of the path of movement of the magnet and back into operative engagement with the first-mentioned roll.

8. An apparatus for unwinding coils of permeable strip comprising a pair of axially adjustable spindles for engaging the center of a coil at its ends and supporting it for rotation, means for delivering a coil to a position adjacent said spindles, means for holding a coil in a selected position on said last-mentioned means, means for moving said first-mentioned means to register a coil mounted thereon in position to receive said spindles, means for adjusting said spindles to engage them in the ends of the coil, means on said spindles for straightening the sides of a coil as the spindles are moved into a coil, a magnet for engaging the free end of a coil, means for moving said magnet into and out of engagement with a coil mounted on said spindles, said straightening means being constructed to permit such operation, a stripping roll disposed to engage the strip as it is pulled from the coil by the magnet, a second stripping roll mounted for movement to and from the first-mentioned roll but disposed when in operative position in the path of movement of said magnet, means for moving said second roll out of the path of movement of the magnet and back into operative engagement with the first-mentioned roll, a third roll cooperating with said other two rolls for straightening the strip, and means for driving one of said rolls to pull the strip from the coil.

9. An apparatus for unwinding coiled material comprising a pair of axially adjustable spindles for engaging a coil at its center and supporting

it for rotation, a platform pivoted at one end mounted below said spindles for rolling a coil on its side thereunder, a cradle for receiving the coil at the end of said platform and directly below said spindles, and means for moving the free end of said platform toward and from said spindles.

10. An apparatus for unwinding coiled material comprising a pair of axially adjustable spindles for engaging the center of a coil at its ends and supporting it for rotation, means for engaging and stripping the free end from a coil mounted on said spindles, a cradle disposed below said spindles for lifting a coil into registration therewith, a roll comprising a part of the coil-supporting structure of said cradle, and means for driving said roll to rotate a coil mounted thereon so as to place the outer end of the coil in the proper position for engagement by said end-engaging means.

11. An apparatus for unwinding coils of permeable strip comprising a pair of axially adjustable spindles for engaging the center of a coil at its ends and supporting it for rotation, means for adjusting said spindles to engage them in the ends of the coil, a magnet for engaging the free end of a coil mounted on said spindles, means for moving said magnet into and out of engagement with the coil, a stripping roll disposed to engage the strip as it is pulled from the coil by the magnet, a second stripping roll mounted for movement to and from the first mentioned roll but disposed when in its normal operative position to lie in the path of movement of said magnet, and means for moving said second roll out of the path of movement of the magnet and back into operative engagement with the first-mentioned coil.

12. An apparatus according to claim 11 employing a third roll co-operating with the two stripping rolls for straightening the strip.

13. An apparatus according to claim 11 in which a third roll is provided which co-operates with the two stripping rolls for straightening the strip and means for adjusting one of said stripping rolls with respect to the others to vary the strip straightening action.
